UNITED STATES PATENT OFFICE.

HERBERT W. BEATTIE, OF QUINCY, MASSACHUSETTS, ASSIGNOR TO THE SILL STOVE WORKS, OF ROCHESTER, NEW YORK.

DESIGN FOR A HEATING-STOVE.

SPECIFICATION forming part of Design No. 33,008, dated July 24, 1900.

Application filed June 20, 1900. Serial No. 21,022. Term of patent 14 years.

To all whom it may concern:

Be it known that I, HERBERT W. BEATTIE, a citizen of the United States, residing in the city of Quincy, county of Norfolk, and State 5 of Massachusetts, have invented and produced a new and original Design for a Heating-Stove; and I do hereby declare the following to be a full, clear, and exact description of the same, in connection with the accompanying drawing, forming a part thereof.

My design embodies the shape and configuration of the stove shown and the ornamentation applied thereto.

In the drawing I have shown a perspective 5 view of a heating-stove embodying my design, in which—

The letter A indicates the lower base-section, having the legs B and containing the scroll-and-leaf surface ornamentation, substantially as shown.

C indicates the upper base-section, tapering slightly toward the upper portion and rounded at the top, having the ornamented sides and at the front the ash-pit door D, provided with the damper-openings and the scroll-and-leaf ornamentations around them.

E indicates the fire-pot section, tapering slightly downwardly and vertically corrugated, as shown, the upper rounded shoulders F at the top being also ornamented at the sides.

G indicates the side rails or aprons, extend-

ing partly over the fire-pot section and provided with the depending arms H, which, together with the rails themselves, are provided with the scroll-and-leaf ornamentation shown. 35

J indicates a front panel having the ornamental border.

K indicates the front door, having the mica 40 openings and a circular damper therein, the portion around the damper and openings being provided with the scroll-and-leaf ornamentations shown, and at the upper portion of the door is provided the ornamental panel 45 L. The frame around the door K embodies the narrower ornamental border or beading M, and outside of this the conventionalized leaf-and-scroll ornamental border N.

O indicates the top section, having the plain 50 flange or band P and above this ornamental zones Q and R, separated by the band S. At the extreme top of the section is the vase-like ornament T.

The design of the stove and the ornamentation shown gives the stove as a whole a most pleasing and attractive appearance. 55

I claim—

The design for a heating-stove, substantially as herein shown and described.

HERBERT W. BEATTIE.
